ATTORNEY

UNITED STATES PATENT OFFICE.

JOHN C. DUEBER, OF CANTON, OHIO.

DESIGN FOR A WATCH-CASE.

SPECIFICATION forming part of Design No. 21,548, dated May 17, 1892.

Application filed March 21, 1892. Serial No. 425,861. Term of patent 14 years.

To all whom it may concern:

Be it known that I, JOHN C. DUEBER, a citizen of the United States, and a resident of Canton, county of Stark, State of Ohio, have invented a new Design for Watch-Cases, of which the following is a full, clear, and exact description, reference being had to the accompanying drawings, making part of this specification.

Figure 1 is a perspective view of a watch-case, showing my design; and Fig. 2 is an edge view of the same.

The leading features of my design are the plain oval rim, the raised ornamental bead or rope at the edge of the lid, and the beveled portion adjacent thereto, to which radiate from the center of the case oval ribs.

A is the plain circular portion at the center of the front and back ribs; B, oval ribs radiating therefrom; D, the circular beveled portion; E, the raised ornamental bead or ²⁰ rope, and F the plain oval rim between the edges of the lids.

What I claim is—

The design for a watch-case, herein shown and described.

In testimony whereof I have hereunto set my hand this 15th day of March, A. D. 1892.

JOHN C. DUEBER.

Witnesses:

W. K. MILLER,
CHAS. R. MILLER.
